UNITED STATES PATENT OFFICE.

HENRY JANSSEN AND FERDINAND THUN, OF READING, PENNSYLVANIA.

BRAIDING-MACHINE.

SPECIFICATION forming part of Letters Patent No. 664,047, dated December 18, 1900.

Application filed August 24, 1897. Serial No. 649,402. (No model.)

To all whom it may concern:

Be it known that we, HENRY JANSSEN and FERDINAND THUN, citizens of the United States, residing at Reading, county of Berks, 5 State of Pennsylvania, have invented certain Improvements in Braiding-Machines, of which the following is a specification.

Our invention consists in certain improvements in braiding-machines, which are fully 10 described in connection with the accompanying drawings, and particularly pointed out in the claims.

The novel construction of braid herein referred to as a product of our improved machine is fully described and claimed in a separate application filed by us January 11, 1900, 15 Serial No. 1,030.

Figure 1 is a plan view, partly in section, of the main portion of a machine embodying our 20 improvements. Fig. 2 is an elevation of the same. Fig. 3 is an enlarged plan view, and Fig. 4 an enlarged sectional elevation, of the transversely-moving carrier mechanism. Figs. 5 and 6 are face views of the braid made 25 by the within-described machine. Fig. 7 is a sectional view showing the relative location of such interwoven threads. Fig. 8 illustrates a modified construction of our additional carrier mechanism; and Figs. 9 and 10 indicate 30 another modified arrangement.

A and B represent the bottom and top plates, respectively, of a braiding-machine of ordinary construction, between which are mounted the usual intermeshing series of carrier-driving gears C', the upper disks c of 35 which engage and traverse bobbin-carriers D in the usual intersecting serpentine guide-grooves b b', which curve around the driving-gear spindles or posts C.

40 The construction and operation of the parts referred to need not be more fully described, inasmuch as they are intended to represent a form of machine such as is commonly used in producing the ordinary braid, either flat or tubular.

45 The object of our present improvements is to provide for producing braid in which are interwoven additional threads, preferably of a different color from the main threads, so as 50 to serve as a filling, whereby the body of the fabric is increased and an ornamental effect produced on one face thereof. For this pur-

pose we employ, in combination with the usual braiding-machine mechanism already referred to, a second series of bobbin or thread carriers E. These latter, as shown in the main views of the drawings, are arranged to travel across the serpentine path b of the first series of carriers by means of the following mechanism: The base-plate e of each carrier 55 E is toothed at e' to form a rack, which is guided in radially-arranged ways F F', one of which is located directly above the gear C', while the other is outside of the serpentine groove b and in alignment with the first, the 60 two sections being separated so as to permit the free passage between them of the first series of carriers D. To give motion to the carriers E, we make the posts or spindles C hollow, and pass through the same rods or shafts 65 G, Figs. 3 and 4, each carrying at its upper end a pinion g, which meshes with a rack-engaging pinion H, whereby the base-plate e of the carriers E is moved inward or outward in the guideways E. A similar pinion mechanism g' H' is provided in connection with the outside guideway F', to which pinions the 70 same movement is transmitted and which operate upon the toothed carrier-plate as the latter is moved from one guideway F into the 75 other F' across the intervening space through which the series of braiding-carriers D pass. As shown, the required simultaneous movement of the pinion mechanism is produced by means of a toothed quadrant I, located under the plate A, which meshes with pinions g² and g³, Figs. 1 and 4, on the lower ends of the shafts G and G', respectively, and to which a rocking motion is given by means of a suitable crank connected to an operating-shaft J. 80 A regular reciprocating motion is thus given to the carriers E in a radial direction and across the path b of the carriers D, thus weaving the threads carried by the reciprocating bobbins into one face of the double braid produced by the action of the braiding-carriers, 85 thereby increasing the body of the fabric and at the same time producing a figured design. 90

In Figs. 5, 6, and 7 the filling-threads, which are indicated by the letter k, are at different 95 points inside or outside of the braiding-threads k' of the outer face, as determined by the movement of the carriers E, while the other face has the same appearance and tex-

ture as ordinary braid, which latter may of course be produced without variation on the same machine by merely throwing out of service the extra carriers E.

- 5 In Fig. 1 it will be noticed that two of the guideways F F' are represented as provided each with two instead of one transversely-moving bobbin-carriers, which are marked, respectively, E and E', these being arranged 10 to move in opposite directions across the serpentine way b b' of the braiding-carriers, thereby increasing the number of filling-threads thus woven into the braid and correspondingly modifying the effect.
- 15 In the modified construction indicated in Fig. 8 the shafts G² G³ are given a vertical instead of rotary motion and carry racks g⁴ g⁴, which operate double pinions H² H³, which are arranged to engage the toothed base-plate 20 e² of the carrier E³, so as to move the latter to and fro in the manner previously described. In the further modified construction indicated in Figs. 9 and 10 similar shafts G² G³ are employed, carrying racks g⁴ g⁴, through 25 which the toothed base-plates e² of the carriers E² are moved across the paths of the threads t, extending from the braiding-carriers D to the take-up mechanism, the guides for the carriers E² consisting in this construction of bars F² F³, supported on brackets m m' a sufficient distance above the grooved plate B, as shown.
- 30 It is evident that other modifications may also be devised without departing from the spirit of our invention, and we do not therefore desire to limit ourselves to the particular construction described.

What we claim is—

1. The combination with the grooved bed-plate of a braiding-machine and with bobbin-carriers guided therein in intersecting serpentine courses of other bobbin-carriers arranged to cross one of said serpentine courses between the intersections of said courses substantially as set forth. 40

2. The combination with the grooved bed-plate of a braiding-machine and with bobbin-carriers guided therein in intersecting serpentine courses of carrier-driving gears therefor having hollow shafts around which the intersecting courses curve, and other bobbin-carriers guided transversely to said courses between the intersections thereof, with mechanism for operating the latter through said hollow shafts substantially as set forth. 50

3. The combination with the grooved bed-plate of a braiding-machine and with bobbin-carriers guided therein in intersecting serpentine courses of other bobbin-carriers having toothed base-plates, guides for each of 60 said toothed base-plates and separate pinions for successively engaging the same located respectively inside and outside of one of said serpentine courses between the intersections and jointly operated to traverse the carriers 65 across the latter substantially as set forth.

In testimony whereof we affix our signatures in presence of two witnesses.

HENRY JANSSEN.
FERDINAND THUN.
